US0D1082459S

(12) **United States Design Patent** (10) **Patent No.:** **US D1,082,459 S**
(45) **Date of Patent:** **** Jul. 8, 2025**

(54) **SNACK BOX**

(71) Applicant: **Guangdong Jintai Technology Co., Ltd.**, Shaoguan (CN)

(72) Inventor: **Sixuan Xu**, Yueyang (CN)

(73) Assignee: **Guangdong Jintai Technology Co., Ltd.**, Shaoguan (CN)

(**) Term: **15 Years**

(21) Appl. No.: **29/984,591**

(22) Filed: **Jan. 15, 2025**

(30) **Foreign Application Priority Data**

Jan. 10, 2025 (CN) 202530015694.5

(51) **LOC (15) Cl.** **07-07**

(52) **U.S. Cl.**

USPC **D7/703**

(58) **Field of Classification Search**

(57) **CLAIM**

The ornamental design for a snack box, as shown and described.

DESCRIPTION

FIG. 1 is a top perspective view of a snack box, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is the snack box in a closed state.

The broken lines in the drawings illustrate the portions of the snack box, which form no part of the claimed design.

1 Claim, 9 Drawing Sheets
